UNITED STATES PATENT OFFICE

1,924,437

CHIMNEY FLUE COVER

John A. Johnson, Crawfordsville, Ind., assignor
to National Supply & Service Corporation

Application August 17, 1932. Serial No. 629,106

8 Claims. (Cl. 126—319)

The common practice in closing flue openings in a wall is with a metal shield which becomes red hot at times and often results in damage by fire to the building or to the wall paper or other decorations, and a principal object of this invention is to provide a flue hole stop that will eliminate all fire hazard.

Often the flue opening or the thimble therein is irregular or out of round making the application of a symmetrical closing device impractical insofar as effecting a complete closure of the opening is concerned, and another important object of my invention is to provide a stop that can be easily applied to completely close any opening regardless of its distorted shape or condition.

My invention contemplates the use of an outside wall plate, an expansible refractory heat insulating material in the opening between the plate and flue and an object of my invention is to provide means operated from in front of the plate for expanding or diametrically extending the refractory material.

Another object is to provide means for attaching the refractory material to the plate and for providing a dead air space between the material and plate as an additional safeguard against fire.

I accomplish the above and other objects which will hereinafter appear by the means exemplified in the accompanying drawing, in which—

Fig. 1 is a fragment in elevation of the inside wall of a flue showing my invention assembled ready for the expansion of the refractory material.

Fig. 2 is a vertical section on the line 2—2 of Fig. 1, showing the position of the expanded refractory material in dotted lines, and

Fig. 3 is a fragment in elevation of the room side of the wall with my invention assembled at a flue opening ready for the expansion of the refractory material.

Like characters of reference indicate like parts in the several views of the drawing.

Referring to the drawing 4 is the flue wall in which 5 is the flue side, 6 the room side, 7 the flue opening and 8 a metal thimble, all of usual and well known construction.

While the flue opening and thimble are here shown circular and regular, for convenience in drafting, they are in practice very often irregular and out-of-round.

A sheet metal wall plate 9 is circular in outline and is large enough in diameter to reach a

suitable holding distance beyond the entrance area of the opening. A bolt hole is formed at the center of the plate with the metal around the hole flanged inwardly to provide a countersink 10, to retain the beveled head 11 of a screw-bolt 12 which is inserted through the hole in the plate.

Located with its edges contacting the inner side of the plate 9 is a cone shaped disc 13, which has a hole at its apex through which the bolt 12 passes.

Also mounted on the bolt 12 is a second cone disc 14 with the slope of the cone in opposite direction to that of disc 13 and having an apex hole for the passage of the bolt. Both discs 13 and 14 are of somewhat less diameter than the normal diameter of the flue opening.

On a threaded end of bolt 12, on the flue-side of disc 14, is a nut 15, and the apex of the cone of disc 14 is formed around the bolt hole into a square socket 16, which serves as a seat for the nut 15 to prevent rotation of the nut when bolt 12 is rotated and disc 14 held from rotation.

Between the two discs 13 and 14 is an expansible refractory material 17, here shown as including a compactible asbestos, but spun glass and any other suitable expansible refractory material may be used.

Initially the dimensions of the material 17 are such as to be readily insertable in the flue opening or thimble with its retaining cone discs. But after such insertion, with the wall plate 9 against the room wall, the material 17 is expanded circumferentially as shown by the dotted lines in Fig. 2, by moving the two cone discs 13 and 14 toward each other by the proper rotation of the screw bolt 12. This is accomplished by the aid of a screw driver applied to the indented head of the bolt and the screw is turned until the expanded refractory material compressively touches the flue opening, or thimble if there is one, all around. This will occur regardless of the irregular or out of round shape of the flue opening or thimble. The friction of the disc 14 against the material 17 holds the disc from rotation by the screw driver.

Further security against fire is insured by the holding of the material 17 out of contact with the plate 9, and also by the creation of a dead-air space 20 between the plate 9 and disc 13.

While I have here shown and described the best embodiment of my invention now known to me it is obvious that changes may be made in the composition of the expansible refractory

material and in the mechanism by which said material is expanded. Therefore, I desire to have it understood that all changes may be resorted to when desired as fall within the scope 5 of the appended claims.

I claim:

1. A stop for a flue opening comprising a plug of expansible heat insulating material and means for expanding the material diametrically 10 to compressively fit the flue opening after insertion of the material therein.
2. In a stop for a flue opening, an outside plate, a plug of expansible heat insulating material in the opening, and means operated from 15 in front of the plate for expanding the material.
3. In a stop for a flue opening, an outside plate, a mass of expansible heat insulating material in the opening, spaced in the opening from the plate, and means for diametrically expanding 20 the material.
4. In a stop for a flue opening, an outside plate, a cone shaped disc with its open side toward the plate, a second cone shaped disc with its open side turned away from the plate, an expansible heat insulating material between the two discs, and a bolt passing through the plate, the material and both discs, said bolt being employed to draw the two cones toward each other to compress said material to cause it to expand 25 diametrically into compressive contact with the circumferential wall of the flue opening.
5. In a stop in combination with a flue having an opening, an outside plate, a disc carried within the opening in spaced relation to the plate to define a dead air space therebetween, a plug of compressible, heat insulating, resilient, refractory material back of the disc, and a second disc back of the material, said two 30

discs being adapted to be drawn compressively against the material to cause the material to expand diametrically and resiliently compressively press against the wall of the flue opening.

6. In a stop for a flue opening, an outside plate, a cone shaped disc with its apex turned away from the plate, a second cone shaped disc with its apex turned toward the plate, an expansible heat insulating material between the two discs, and a bolt passing through the plate, 80 the material and both discs, said bolt being employed to draw the two cones toward each other to compress said material to cause it to expand diametrically into compressive contact with the circumferential wall of the flue opening, both of said discs being of less diameter than the normal diameter of the flue opening for which the stop is to be used.

7. In a stop for a flue opening, a disc, a second disc, a resilient heat insulating material 85 between the two discs, and a bolt passing through the material and both discs, said bolt being employed to draw the two discs toward each other to compress said material to cause it to expand diametrically into compressive contact entirely 90 circumferentially around the wall of the flue opening affording a seal thereby.

8. In a stop for a flue opening, a disc, a second disc, a resilient heat insulating material between the two discs, and a bolt passing through 105 the material and both discs, said bolt being employed to draw the two discs toward each other to compress said material to cause it to expand diametrically into compressive contact entirely 110 circumferentially around the wall of the flue opening affording a seal thereby, both of said discs being smaller than the flue opening.
